UNITED STATES PATENT OFFICE

131,832

DESIGN FOR A JEWELRY COMPONENT OR SIMILAR ARTICLE

Joseph H. Fisher, Brookline, Mass.

Application February 6, 1942, Serial No. 105,664

Term of patent 3½ years

To all whom it may concern:

Be it known that I, Joseph H. Fisher, a citizen of the United States, residing at Brookline, in the county of Norfolk in the Commonwealth of Massachusetts, have invented a new, original, and ornamental Design for a Jewelry Component or Similar Article, of which the following is a specification, reference being had to the accompanying drawing, forming a part thereof, in which:

Figure 1 is a front elevational view of a jewelry component showing my new design, and Figure 2 is a sectional view taken on the line 2—2 of Figure 1.

I claim:

The ornamental design for a jewelry component or similar article, substantially as shown.

JOSEPH H. FISHER.
